SHOWER STALL

Lawrence E. Wolske, Benton Harbor, Mich., assignor to
Whirlpool Corporation, a corporation of Delaware

Filed Sept. 14, 1966, Ser. No. 3,862

Term of patent 14 years

(Cl. D4—4)

FIGURE 1 is a perspective view of a shower stall embodying my new design;

FIGURE 2 is a front elevation thereof;

FIGURE 3 is a fragmentary vertical section taken substantially along the line 3—3 of FIGURE 2, the depth of the design embossment in the bottom wall shown in dotted lines in FIGURES 1 and 4 being insufficient to permit illustration thereof in the small scale illustration of FIGURE 3;

FIGURE 4 is a horizontal section taken substantially along the line 4—4 of FIGURE 2;

FIGURE 5 is a perspective view of a modified form of shower stall provided with a dome;

FIGURE 6 is an enlarged front elevation thereof;

FIGURE 7 is a vertical section taken substantially along the line 7—7 of FIGURE 6, the depth of the design embossment in the bottom wall shown in dotted lines in FIGURES 5 and 9 being insufficient to permit illustration thereof in the small scale illustration of FIGURE 7;

FIGURE 8 is a fragmentary vertical section thereof taken substantially along the line 8—8 of FIGURE 7; and

FIGURE 9 is a horizontal section thereof taken substantially along the line 9—9 of FIGURE 6.

The bottom and rear views are omitted as being hidden in normal installation and define no part of the invention.

The dominant features of my invention are shown in solid lines.

I claim:

The ornamental design for a shower stall, as shown and described.
